(57) **CLAIM**

The ornamental design for a hand guard, as shown and described.

DESCRIPTION

FIG. 1 is a front perspective view of my new and ornamental design for a hand guard;

FIG. 2 is a top view thereof;

FIG. 3 is a top perspective view thereof, fitted on a hand; and,

FIG. 4 is a bottom view thereof, fitted on a hand.

The broken line showing of a human hand is for illustrative purposes only and forms no part of the claimed design.

1 Claim, 2 Drawing Sheets

FIG. 1

FIG. 2
